US00D707124S

(12) **United States Design Patent**
Blain et al.(10) **Patent No.:** US D707,124 S
(45) **Date of Patent:** ** Jun. 17, 2014(54) **BOTTLE CAP**4,390,432 A 6/1983 Takeguchi et al.
4,416,854 A 11/1983 Nielsen
4,559,478 A 12/1985 Fuller et al.(75) Inventors: **Christopher C. Blain**, Sausalito, CA
(US); **Derek Gavin Sullivan**, Oakland, CA (US)

(Continued)

(73) Assignee: **CamelBak Products, LLC**, Petaluma, CA (US)

FOREIGN PATENT DOCUMENTS

AU 199859637 B2 1/2001
CA 2279860 7/2007(**) Term: **14 Years**

(Continued)

(21) Appl. No.: **29/417,283**

3,500,041 A	3/1970	Kassing
3,843,521 A	10/1974	Zeff
3,906,236 A	9/1975	Callahan
3,970,856 A	7/1976	Mahaffey et al.
4,066,551 A	1/1978	Stern
4,101,777 A	7/1978	Reid
4,184,076 A	1/1980	Kosnoff
4,274,970 A	6/1981	Beitzel
4,276,256 A	6/1981	Karamian
4,296,328 A	10/1981	Regan

FIG. 1 is a top isometric view of a bottle cap showing the new design.

FIG. 2 is a front view of the new design.

FIG. 3 is a rear view of the new design.

FIG. 4 is a left side view of the new design, with the right side view being a mirror image thereof.

FIG. 5 is a top view of the new design; and,

FIG. 6 is a bottom view of the new design.

In the drawings, the broken lines depict environmental subject matter only and form no part of the claimed design.

1 Claim, 3 Drawing Sheets
